UNITED STATES PATENT OFFICE

DEWEY H. BITNEY, OF ALBION, MICHIGAN, ASSIGNOR TO UNION STEEL PRODUCTS COMPANY, OF ALBION, MICHIGAN

STRUCTURAL UNIT

Application filed August 16, 1929. Serial No. 386,282.

The main objects of this invention are:

First, to provide a structural unit by means of which pencil rods, furring strips, metal lathing and the like may be effectively attached to I beams and joists or studding.

Second, to provide a structural unit of this character which provides space between the supporting element and the edges of the beams, joists, studding or the like in which 10 electric cables, pipes or conduits may be laid.

Third, to provide a structural unit of the class described which can be quickly attached to beams or structural elements having flanges varying considerably in length.

15 Objects pertaining to details and economies of my invention will definitely appear from the description to follow. The invention is defined in the claims.

A structure embodying the features of my 20 invention is clearly illustrated in the accompanying drawings, in which:

Fig. 1 is a fragmentary perspective view of one of my improved structural units, one of the supported elements being indicated by 25 dotted lines.

Fig. 2 is a fragmentary section on a line corresponding to line 2—2 of Fig. 4 illustrating the structural unit in operative relation to a plurality of I beams or joists and to 30 a supported element, that illustrated being a pencil rod.

Fig. 3 is an enlarged fragmentary view in section on line 3—3 of Fig. 2.

Fig. 4 is an inverted fragmentary view 35 further illustrating the manner of engaging the hooks with the supporting element.

In the accompanying drawings, 1 represents structural elements or beams of I cross section. My improved structural unit comprises a longitudinal rod 2 which in practice 40 is of substantial length and to which I secure a plurality of hangers or support engaging members 3 formed of wire and disposed in transverse spaced relation on the longitudinal rod. These members are secured or fixed 45 to the rod 2 by welding.

The members 3 are provided with hooks 4 at their upper ends, the hooks of alternate hangers being disposed in oppositely facing 50 relation so that they may be engaged with

opposite edges of the bottom flange of a structural element such as the I beams 1. The lower ends of the hangers are turned laterally providing attaching members 5 disposed longitudinally of the supporting rod and in an upwardly inclined relation thereto so that an element to be supported, such as the pencil rod 6, may be engaged with the attaching members by springing the attaching members.

The metal lathing or furring strips, or other articles thereby supported, may be adapted to these pencil rods, or the pencil rods may be omitted and the element thereby supported attached direct to the hangers.

A further advantage resulting from the use of these structural units is that space is provided below the beams 1 to receive electric cables as indicated at 7, or other pipes or conduits.

The hooks may be readily engaged with their support and the hangers are easily engaged with the flanges or parts of supporting elements of different width, the longitudinal bars or the hangers being sprung sufficiently 75 not only to permit engagement but to accommodate such variation in width.

I have illustrated and described my improvements in an embodiment which I have found very satisfactory. I have not attempted to illustrate or describe various adaptations which I contemplate as it is believed this disclosure will enable those skilled in the art to embody or adapt the same as may be desired.

Having thus described my invention what I claim as new and desire to secure by Letters Patent is:

1. A structural unit comprising a longitudinal supporting rod, and a plurality of hangers disposed transversely thereof in spaced relation and fixedly secured thereto and having hooks at their upper ends adapted to be engaged with the flange of a beam or like structural element, the hooks of adjacent hangers facing oppositely, said hangers having laterally turned portions at their lower ends disposed longitudinally of the rod and with their ends inclined toward the rod providing attaching members which may be 100

sprung to receive an element to be supported.

2. A structural unit comprising a longitudinal supporting rod, and a plurality of support engaging members fixed to said rod in spaced relation to project at each side thereof and having hooks at one end engageable with the flange of a beam or like structural element with the hooks of adjacent support engaging members disposed to engage opposite edges of the supporting element, said support engaging members having laterally turned portions at their opposite ends disposed longitudinally of the rod providing attaching members with which an element to be attached may be engaged.

3. A structural unit comprising a longitudinal supporting rod, and a plurality of support engaging members fixed to said rod in spaced relation to project at each side thereof and having hooks at one end engageable with the flange of a beam or like structural element with the hooks of adjacent support engaging members disposed to engage opposite edges of the supporting element, said support engaging members having portions at their opposite ends providing attaching members for an element to be attached.

4. A structural unit comprising a longitudinal rod, and a plurality of support engaging members fixed to said rod in spaced transverse relation thereto and having hooks at one end engageable with a supporting element, part of the hooks facing in one direction and the remainder in the opposite direction whereby the hooks may be engaged with opposite edges of the supporting element, the opposite ends of said support engaging members constituting attaching members for an element to be attached.

5. A structural element comprising a springable longitudinal supporting rod, and a plurality of hangers fixed in spaced relation transversely of said rod and having hooks at their inner ends disposed with the hooks of adjacent hangers facing in opposite directions and engageable with opposite edges of a structural element by springing the longitudinal rod, said hangers having attaching members at their outer ends.

6. A structural element comprising a springable longitudinal supporting rod, and a plurality of hangers fixed in spaced relation transversely of said rod and having hooks at their inner ends disposed with the hooks of adjacent hangers facing in opposite directions and engageable with opposite edges of a structural element by springing the longitudinal rod.

60 In witness whereof I have hereunto set my hand.

DEWEY H. BITNEY.
